UNITED STATES PATENT OFFICE.

FREDERICK MAX PORITZ, OF NEW YORK, N. Y., ASSIGNOR TO MODERN LIGHTING FIXTURE CO., INC., A CORPORATION OF NEW YORK,

DESIGN FOR A LIGHTING-FIXTURE PART.

Application filed September 17, 1924. Serial No. 10,803. Term of patent 3½ years.

To all whom it may concern:

Be it known that I, FREDERICK MAX PORITZ, a citizen of the German Republic, and a resident of the city, county, and State of New York, have invented a new, original, and ornamental Design for Lighting-Fixture Parts, of which the following is a specification, reference being had to the accompanying drawing, forming a part hereof.

The drawing shows an elevational view of the lighting fixture part.

I claim:

The ornamental design for a lighting fixture part substantially as shown.

FREDERICK MAX PORITZ.
